UNITED STATES PATENT OFFICE.

JOHN GREEN, OF ST. LOUIS, MISSOURI, ASSIGNOR OF ONE-HALF TO
ROBERT M. COLLINS, OF SAME PLACE.

ATTACHMENT FOR CUTTER-HEADS.

SPECIFICATION forming part of Letters Patent No. 271,199, dated January 23, 1883.

Application filed June 12, 1882. (No model.)

To all whom it may concern:

Be it known that I, JOHN GREEN, of the city of St. Louis, in the State of Missouri, have invented a certain new and useful Improvement in Knife Attachments for Cutter-Heads, of which the following is a full, clear, and exact description, reference being had to the accompanying drawings, forming part of this specification, and in which—

10 Figure 1 is a side view, Fig. 2 an end view, and Figs. 3 and 4 perspective views, of the knife or cutter clamps, Fig. 4 being inverted.

15 My improvement relates to the manner of securing to the head the knives or cutters of a molding-machine; and my improvement consists in providing each cutter with a clamp or clamps having bearing in grooves made in the head, as hereinafter set forth.

20 B represents the head, and B its turning shaft. C are the knives, and D strengthening-pieces. These are all of common construction, and the head has the usual T-shaped grooves, A'.

25 E are the clamps, each consisting of a rib, E', which fits in the largest part of the groove A', a web, E², fitting the neck of the groove, shoulders E³ E³, which give strength to the web, and head or lip E⁴ for clamping the knife.

F are set-bolts, which pass down through the heels of the clamps, whose lower ends bear

against washers F' on the bottom of the 30 grooves A'.

The shoulders E³ are formed so as not to bear upon the head, and the tops of the ribs E' are oval in form, so that by tightening on the set-screws the clips or clamps will rock 35 and take a firm hold of the cutter, and different thicknesses of cutters may be used. The ribs E' are thrown forward by extensions E⁵ of the webs, so as to bring them nearly or quite beneath the lips E⁴, thus increasing the 40 power of the clamps. In light work only one clamp would be absolutely necessary for each knife.

I claim—

1. The cutter-clamp herein described, formed 45 with a rib, E', web E², shoulders E³ E³, and lip E⁴, as set forth.

2. A cutter-clamp, E, formed with a rib, E', web E², shoulders E³ E³, lip E⁴, and extension E⁵, as set forth.

3. The cutter-clamp E, having rib E', web 50 E², shoulders E³ E³, and lip E⁴, the set-screw or bolt F, and washer F', in combination with a head, A, having T-grooves A', as set forth.

JOHN GREEN.
